Primary Examiner — Erich G Herbermann*Assistant Examiner* — Altaira J Swangin(74) *Attorney, Agent, or Firm* — Bartholomew Law PC; Michael Bartholomew(57) **CLAIM**

The ornamental design for an expansion screen as shown and described.

DESCRIPTION

FIG. 1 is a front, right and top perspective view of an expansion screen, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1; and,

FIG. 10 is an enlarged view of detail 10 in FIG. 2.

The even-dash broken lines depict portions of the expansion screen that form no part of the claimed design. The dot-dash broken lines in FIGS. 1, 2, 9 and 10 represent the limits of the enlarged detail views and form no part of the claimed design.
